EDWARD B. FUQUA, OF MEMPHIS, TENNESSEE

AIR PUMP

Application filed October 22, 1928. Serial No. 314,046.

In many cases water is pumped from a well and delivered to a storage tank against air pressure. In such tank the expansion of the air in the tank is counted on to maintain pressure for delivery purposes. It is found that the supply of air gradually diminishes so that it is necessary frequently to replace the supply or at least to augment it. To accomplish this it has become the custom to provide some kind of air pump in connection with the ordinary water pump, and this invention relates to such air pump and especially to such pumps for use in connection with deep well pumps whereby air under pressure may be supplied to the water raised from the well and with such water be carried to the tank or some other suitable receptacle in which it is desired to maintain a supply of air for expansion purposes.

The objects of my invention are:

(a) To provide an air pump which is simple and efficient in action and which may be actuated from the ordinary deep well pump rod;

(b) To provide means for discontinuing the action of the pump at certain times; and

(c) To generally simplify and improve the design and construction of such a device.

The means by which the foregoing and other objects are accomplished and the manner of their accomplishment will readily be understood from the following specification on reference to the accompanying drawings, in which:

Fig. 1, is a sectional elevation taken substantially on the line I—I of Fig. 3;

Fig. 2, is a sectional plan on the line II—II of Fig. 1 looking upward; and

Fig. 3, is a similar sectional plan taken on the line III—III of Fig. 1.

Referring now to the drawings in which the various parts are indicated by numerals, 10 is a fragmentary portion of the power head casing of an ordinary deep well pump, and 11 a hollow boss integral with the casing and extending forwardly therefrom. 12 is the well pipe which extends downward in the well. 13 is the pump rod. The upper end of this rod is reduced slightly in diam-

eter leaving annular shoulders 14 and 15, between which shoulders some form of attaching means may be used to secure the rod to the pump head operating mechanism, not

55
The rod 13 is provided with threads 16, and a nut 17 is screwed thereon. The upper portion of this nut is cylindrical and the lower portion preferably is squared up to receive a wrench. 18 is the cup leather which 60 is held down against the nut 17 by a second nut 19 which nuts together with the cup leather form the air pump plunger. 20 is an air pump cylinder, which is disposed in and secured to an annular flange 21. This 65 flange in turn is carried by the hollow boss 11 to which it is preferably secured by screws 22. The lower end of the cylinder 20 projects below the flange 21 preferably extending somewhat below the upper end of the 70 pipe 12. The lower end of the cylinder 20 is closed by a head 23 which may be secured to the cylinder as by the rivets 24. The piston rod 13 passes centrally through this head 75 and ordinarily is fairly closely embraced thereby, but no attempt is made to make a water or air tight joint between these parts. 25 is an annular cylindrical extension integral with the head 23 and depending below the same. 26 is an annular flange preferably secured on the lower end of the annular cylinder 25 by threads. 27 is an annular plate rotatably mounted on the annular cylinder 25, and snugly seated against the lower surface 80 of the head 23, against which it is held by a compression spring 28. The head 23 and plate 27 are provided respectively with holes or ports 29 and 30 which may be registered to provide passages through the head and the flange. 31 is a shift rod which is turnably mounted in a boss 32, on the head 23, and extends thence upward through the hollow boss 11 and through a stuffing box 33 in the flange 21. The stuffing box 33 provides a mounting for the upper end of the rod 31, 95 in which mounting the rod may be turned. The end of the rod 31 below the boss 32 is bent laterally, substantially at right angles and the end 34 turned upward to form a pin which engages with one of the holes 30 in 100

the plate 27, this hole being slotted to the edge of the plate to permit movement of the pin therein. When the rod 31 is disposed in the position shown in Fig. 3 the ports are shifted out of register.

35 is an air passageway drilled down through the center of the rod 13 to a point below the point of attachment of the air pump plunger and thence connected by a lateral channel 36 into the air cylinder 20. The upper end of the pump rod is provided with a somewhat larger chamber 37 in which is screwed a valve seat against which a valve 39 is held by a compression spring 40.

41 is the water discharge pipe leading from the hollow boss 11 to a storage tank.

The operation of the pump is as follows; with the plate 27 set as shown so that the holes therethrough register with the holes in the air cylinder head, the up stroke of the pump rod 13 would draw air through these openings and on down stroke this air would be forced out through these openings until the water supply brought up from below fills the pipe 12 and the hollow boss 11, after which, movement of the air plunger simply churns water into and out of the air cylinder.

Should however it be desired to force air out through the pipe 41 along with the water discharged, the rod 31 is turned to shift the holes 30 out of register with the holes 29, thereafter on the up stroke the plate 27 seating against the head 23 would cut off the air supply from that direction and cause air to be drawn past the valve 39 and downward through the passage-way 35 into the air cylinder 20. On the down stroke the air plunger would force the air from the cylinder 20 through the holes 29 displacing the plate 27, by compressing the spring 28, and forcing the air out into the water in the pipe 13.

At the end of the stroke the plate 27 immediately seats against the head 23 closing off the holes 29, and on the up stroke the air just forced out of the air cylinder is carried upward with the stream of water pumped from below and discharged through the pipe 41 to such receptacle as may have been provided.

It will be seen that during pumping the operator can at any time readily cut the air on or off as may be desired.

It will also be noted that by raising the well pump rod to bring nut 17 above the air cylinder, the top nut 19 may be unscrewed and the cup leather removed and replaced without necessity of removing pump rod from the well.

Having described my invention, what I claim is:

1. In an air pump, a cylinder, a reciprocable rod disposed axially therethrough, a plunger within said cylinder secured to said pump rod and reciprocable therewith, said pump rod having a chamber therein above said plunger, and a passageway leading

downward therefrom and into said cylinder below said plunger, a valve seat within said chamber, a valve adapted to seat against the under side of said seat, a spring urging said valve against said seat, an annular head surrounding said pump rod, closing the lower end of said cylinder, said head having a plurality of ports therethrough, an annular plate having ports adapted to be registered with the ports in said head, a spring urging said plate against the outer side of said head, and means for shifting said plate to bring said ports into and out of register with the ports in said head, whereby said air pump may be rendered inoperative or operative as the case may be.

2. In an air pump; a cylinder, a reciprocable rod disposed axially therethrough, a plunger within said cylinder secured to said pump rod and reciprocable therewith, said pump rod having a passageway leading downward therethrough into said cylinder below said plunger, a check valve closing said passageway against pressure from within said cylinder, an annular head, surrounding said pump rod, closing the lower end of said cylinder, said head having a plurality of ports therethrough, an annular plate having ports adapted to be registered with the ports in said head, a spring urging said plate against the outer side of said head, and means for shifting said plate to bring said ports into and out of register with the ports in said head whereby said air pump may be rendered inoperative or operative as the case may be.

3. In an air pump; a cylinder, a reciprocable rod disposed axially therethrough, a plunger within said cylinder secured to said rod and reciprocable therewith, said pump rod having a passageway leading downward therethrough into said cylinder below said plunger, a check valve closing said passageway against pressure from within said cylinder, an annular head surrounding said pump rod, closing the lower end of said cylinder said head having a plurality of ports therethrough, an annular plate having ports adapted to be registered with the ports in said head, means yieldably urging said plate against the outer side of said head, and means for shifting said plate to bring said ports into and out of register with the ports in said head, whereby said air pump may be rendered inoperative or operative as the case may be.

4. In an air pump, a cylinder, a reciprocable pump rod extending axially therethrough, a plunger within said cylinder secured to, and reciprocable with, said rod, said plunger having a passageway therethrough, a check valve closing said passageway against pressure from within said cylinder, an annular head surrounding said pump rod, closing the lower end of said cyl-

inder, said head having a port therethrough, an annular plate having a port adapted to be registered with the port in said head, means yieldably urging said plate against the outer side of said head, and means for shifting said plate to bring said ports into and out of register whereby said air pump may be rendered inoperative or operative as the case may be.

- 10 5. In an air pump, a cylinder, a reciprocable pump rod extending axially therethrough, a plunger within said cylinder secured to, and reciprocable with, said rod, said plunger having a passageway therethrough, 15 a check valve closing said passageway against pressure from within said cylinder, an annular head surrounding said pump rod, closing the lower end of said cylinder, said head having a plurality of ports therethrough, 20 an annular plate having ports adapted to be registered with the ports in said head, means yieldably urging said plate against the outer side of said head, and means for shifting said plate to bring said ports into and 25 out of register with the ports in said head, whereby said air pump may be rendered inoperative or operative as the case may be.

In testimony whereof I hereunto affix my signature.

30 EDWARD B. FUQUA.
